UNITED STATES PATENT OFFICE

166,082

SOIL MOISTURE INDICATOR

Oliver J. Knutson, Colorado Springs, Colo.

Application July 7, 1951, Serial No. 15,783

Term of patent 14 years

(Cl. D52—1)

To all whom it may concern:

Be it known that I, Oliver J. Knutson, a citizen of the United States, residing at Colorado Springs, in the county of El Paso and State of Colorado, have invented a new, original, and ornamental Design for Soil Moisture Indicator, of which the following is a specification, reference being had to the accompanying drawing, forming a part thereof.

Figure 1 is a plan view of a soil moisture indicator showing my new design.

Figure 2 is a side elevational view.

Figure 3 is a left end view.

Figure 4 is a right end view.

I claim:

The ornamental design for a soil moisture indicator, as shown.

OLIVER J. KNUTSON.
